(57) CLAIM

The ornamental design for a perfume vaporizer, as shown and described.

DESCRIPTION

FIG. 1 is front view of a perfume vaporizer according to the present invention.

FIG. 2 is a top view of the perfume vaporizer depicted in FIG. 1.

FIG. 3 is a right side view of the perfume vaporizer depicted in FIG. 1.

FIG. 4 is a left side view of the perfume vaporizer depicted in FIG. 1.

FIG. 5 is a bottom view of the perfume vaporizer depicted in FIG. 1.

FIG. 6 is rear view of the perfume vaporizer depicted in FIG. 1; and,

FIG. 7 is a perspective front, top and right side view of the perfume vaporizer depicted in FIG. 1.

The broken lines shown in FIGS. 1 and 5 are included for the purpose of illustrating portions of the perfume vaporizer that form no part of the claimed design. The other portions of the bottom end in FIG. 5 not visible in FIGS. 1, 3, 4 and 6 likewise form no part of the claimed design.
